DESIGN FOR A WALKING PULL TOY

Walter Dorr, Scranton, Pa.

Application September 24, 1946, Serial No. 133,543

Term of patent 3½ years

(Cl. D34—15)

To all whom it may concern:

Be it known that I, Walter Dorr, a citizen of the United States, residing at Scranton, in the county of Lackawanna and State of Pennsylvania, have invented a new, original, and ornamental Design for a Walking Pull Toy, of which the following is a specification, reference being had to the accompanying drawing, forming part thereof.

In the drawing,

Fig. 1 is a side elevational view of a walking pull toy showing my new design, and

Fig. 2 is a front view of the same.

I claim:

The ornamental design for a walking pull toy, substantially as shown.

WALTER DORR.
